Application November 4, 1955, Serial No. 545,086

5 Claims. (Cl. 315—13)

The invention relates to systems for controlling the deflection of electron beams of cathode ray tubes, and it particularly pertains to such systems in which a plurality of electron beams are deflected by common deflection circuitry.

One type of cathode ray tube, or kinescope, with which the invention may be successfully used is a color kinescope of the general form described in an article, "A three-gun shadow-mask color kinescope," by H. D. Law published in the Proceedings of the IRE volume 39, No. 10, for October 1951 at page 1186. The target electrode structure of such a tube comprises in part a luminescent screen in which different phosphor areas produce differently colored light when excited by electron beams impinging from different angles. The angle of impingement determines the particular color of the light produced. For satisfactory operation of such kinescopes, it is necessary to effect substantial convergence of the different electron beams at all points on the raster formed by deflecting the three electron beams in two mutually perpendicular directions. A general discussion of this beam convergence problem will be found in an article entitled, "Deflection and convergence in color kinescopes" by A. W. Friend, published in the Proceedings of the IRE, volume 39, No. 10, for October 1951 at page 1249. One type of multi-beam kinescope to which the invention particularly pertains includes a pair of magnetic pole pieces located internally of the kinescope envelope for each beam. These internally located pole pieces are energized by magnetic components arranged outside the kinescope envelope. These magnetic components may be entirely electromagnetic or they may include some permanent magnetic structure since the internally located pole pieces usually require static as well as dynamic energization. In general, it is desirable to provide such convergence means for kinescopes with the minimum of additional components arranged for maximum ease of adjustment.

An object of the invention is to provide improved circuitry for effecting convergence of the plurality of electron beams of a multi-beam kinescope with passive network elements.

Another object of the invention is to provide improved circuitry for adjusting the convergence of the plurality of beams of a multi-beam kinescope in a color television image reproducing device.

According to the invention parabolic convergence current waves for application to the pole-piece exciting windings of a multi-beam kinescope are obtained by integration of pulse and sawtooth voltage waves in resistive and inductive reactance circuits. The circuit features adjustable resistance elements interposed in series with the leads of one electron beam deflecting winding which in conjunction with the inductance component of the associated beam converging winding provides variable amplitude parabolic current waves flowing through each of the highly inductive beam converging windings. Other resistive elements connected across a centre-tapped isolated winding on the output transformer for the one deflection wave provides variable amplitude positive or negative sawtooth voltage waves at the same deflection rate for tilting the parabolic waves.

A voltage pulse at the frequency of the other electron

2

beam deflecting wave obtained from a secondary winding of the output transformer for the other deflection wave is applied to a plurality of series circuits, each comprising an adjustable inductance element, a compensating capacitor element and a resistance element of low impedance with respect to that of the inductance element. Sawtooth voltages are thus produced at the other deflection rate and the amplitudes thereof may be adjusted by varying the inductances in the series circuits. The converging 10 windings are shunted across the series connected compensating capacitor and resistance element. Upon integration by application of the sawtooth voltages to the highly inductive converging windings variable amplitude current waves of parabolic waveform are produced. The 15 compensating capacitance element provides a more suitable waveform for convergence and also reduces the power loss by permitting the use of larger values of resistance elements. The resulting parabolic current waveform is phase corrected by effectively varying the impedance of the shunt circuits.

According to the invention improved convergence with maximum ease in adjustment is obtained by providing an adjustable differential inductance element and another adjustable inductance element common to the beam converging windings associated with two of the electron beams. Adjustment of the differential element apportions the inductance in each beam converging winding circuit for the same variation with beam deflection angle; leaving the other element to determine the total inductance 20 for proper convergence at all points of the raster. A differential resistance element and another resistance element are connected in common to the two beam converging windings to shift the phase in similar manner.

Further according to the invention, the trajectory of a third electron beam, which may have serious "drooping" with respect to those of the other electron beams, is brought into convergence by shunting the series resistance element by an adjustable inductance component providing an improved dynamic current waveform and 30 permitting the use of adjustable inductors of a single range of values in the series circuits.

In order that the practical aspects of the invention may be fully appreciated, an express embodiment, given by way of example only, is described hereinafter with reference to the accompanying drawing in which:

45 Fig. 1 is a functional diagram of a television receiving apparatus in which the invention may be incorporated;

Fig. 2 is a cross-section view of a multi-beam kinescope of the type to which the use of the invention is particularly applicable; and Fig. 3 is a schematic diagram of an embodiment of the invention.

Referring first to Fig. 1, there is shown a functional diagram of portions of a color television receiver to which the invention is particularly adaptable, and which receiver may otherwise comprise entirely conventional circuitry.

In such a receiver, color television signals appearing at an antenna are applied to a radio frequency wave amplifying circuit and the output therefrom is applied along with the wave obtained from a local beat oscillation generating circuit to a frequency changing circuit. The output of the frequency changing circuit is applied to an intermediate frequency (I-F.) amplifier which may be one having separate channels for picture and sound signals or one having a single channel in which both picture and sound signals are amplified at the same time. The output of the I-F. amplifying circuit is applied at terminals 16 to a video demodulating circuit 17 for deriving a video frequency (V-F.) wave from the television signals. The detected video signals are amplified in a V-F. amplifying circuit 18. Sound signals are further processed in a sound I-F. amplifying circuit, an aural signal discriminating circuit, an audio frequency (A-F.)

amplifying circuit for reproduction by a transducer, usually in the form of a loud speaker. The output of the V.-F. amplifying circuit is applied to a translating circuit 19 for converting luminance and chrominance components into proper form for application to the signal input circuitry of an image reproducing device 20 incorporating a tri-color kinescope. The output of the video frequency amplifying circuit is also applied to a synchronizing pulse separating circuit 24 to separate the synchronizing pulses from the picture signals and to separate the horizontal synchronizing pulses from the vertical. The separated vertical synchronizing pulses are applied to a vertical deflection wave generating circuit 25 and thence to a vertical deflection wave amplifying circuit 26, while the horizontal synchronizing pulses are applied to a horizontal deflection frequency oscillator and frequency control circuit 27 and thence to a horizontal deflection wave amplifying circuit 28. A high voltage and focus voltage generating circuit is coupled to the horizontal deflection wave amplifying circuit to develop focus and ulti potentials for the kinescope. The vertical deflection wave amplifying circuit 26, the horizontal deflection wave amplifying circuit 28, are coupled to the image reproducing device 20 to supply vertical and horizontal deflection waves for deflecting the electron beams of the kinescope. The vertical deflection wave amplifying circuit 26 and the horizontal deflection wave amplifying circuit 28 are connected to a convergence wave generating circuit 30 which may include circuitry according to the invention, for converging the individual beams of the multi-gun kinescope. A low voltage power supply, normally connected to the local A.-C. power lines, is arranged to furnish direct energizing potentials to all circuits. An automatic gain control amplifying and distributing network may be coupled to the synchronizing pulse separating circuit 24 or the video frequency demodulating circuit 17 or to the video amplifying circuit 18 to supply control potentials to the desired ones of the circuits previously mentioned. Normally, the R.-F. and I.-F. amplifying circuits are at least so supplied.

The kinescope of the image reproducing device 20 may be of the same general type as that disclosed in the H. B. Law paper hereinbefore mentioned. The kinescope preferably has a luminescent screen provided with a multiplicity of small phosphor areas arranged in groups and capable of producing light of the different component colors when excited by electrons. In back of and spaced from the screen there is an apertured masking electrode having an aperture for and in substantial alignment with each group of phosphor areas. The luminescent screen and the masking electrode may have planar or partially spherical surfaces; the invention being equally applicable to either form of target electrode structure.

The kinescope also has a plurality of electron beams equal in number to the number of component colors in which the image is to be reproduced. Conventionally, three electron guns, which may be entirely conventional in structure consisting of a cathode, a control electrode and a focusing electrode, are arranged substantially parallel to produce three separate electron beams by which to energize respectively blue, red and green phosphor areas of the screen of the kinescope. The kinescope also contains a beam accelerating electrode, or ulti, consisting of at least one cylindrical "grid" electrode and a conductive wall coating on the inner surface of the envelope of the kinescope and extending out to the region of the target electrode structure. When these electron beams are properly converged at the target structure, the electrons pass through the apertures of the masking electrode from different directions and impinge on different phosphor areas of each of the groups so as to produce light in the three component colors. The electrodes of the kinescope may be energized in the conventional manner and the color information signals are ap-

plied so that the electron beams are modulated in intensity in accordance with the information carried by the color-representative video signals derived from the translator circuit 19. The video signal source will not be described further herein since it does not form in and of itself an essential part of the invention.

Associated with the color kinescope is a deflection system yoke, which may be entirely conventional and, in which may be mounted two pairs of suitably placed windings electrically connected so that, when properly energized, electromagnetic fields are produced to effect angular deflections of the electron beams in both the horizontal and vertical directions to scan the usual rectangular raster at the target electrode structure. Deflection waves for application to the electron beam deflecting windings are obtained from the vertical and horizontal deflection wave amplifying circuits 26 and 28 respectively.

The beam convergence system also includes a plurality of electromagnetic field producing elements arranged about the neck of the kinescope adjacent to the predeflection paths of the electron beams. An example of such construction is shown in Fig. 2 wherein three magnet assemblies 31R, 31G and 31B arranged about the neck of a kinescope envelope 35. The precise location of the magnet assemblies is not necessarily indicated in Fig. 2 but it is to be understood that each of the magnet assemblies is located relative to the path of one of the electron beams to influence that one beam to the virtual exclusion of the others. The magnetic fields produced by these magnet assemblies are transverse to the associated beam paths and in a direction to move the associated beams radially relative to the longitudinal axis of the kinescope. The convergence magnet assemblies 31R—31B are usually energized by a substantially unidirectional current component to effect an initial convergence of the electron beams substantially at the target electrode structure. Normally, convergence is initially made at the center of the screen; however, this initial convergence may be made at any point, for example at one corner of the raster. In order to do this, the unidirectional energizing current component is effected in such a way that the magnet may be individually energized in different magnitudes.

The convergence magnet assemblies 31R—31B are also dynamically energized by wave energy derived from suitable generating means so as to effect a variation in the magnitude of the transverse fields produced and to vary the deflection of the individual electron beams as a function of the overall deflection of the three beams. In this way suitable variations are made in the convergence angles between the various beam components in the individual beams so as to produce the desired convergence of the beams substantially at all points of the target electrode structure. All of the magnet assemblies being the same, only one will be described in detail. Hereinafter the suffixes R, G and B are added to the reference numerals in reference to the components for the Red, Green and Blue exciting electron beams respectively, but the suffix will be dropped where the discussion of the general case is made more clear by so doing. The magnet assembly 31B comprises a core, which may be in one piece, but is shown in two pieces 36B, 37B having legs 38B, 39B extending at right angles to the main body of the core. If direct current is utilized to afford static convergence, the core might conveniently be in one piece. As shown, however, the core of the magnet assembly 31B is split into two pieces 36B, 37B and mounted between the core pieces, in suitable recesses formed therein, is a substantially cylindrical permanent magnet 40B. This magnet is polarized substantially diametrically so as to present north and south poles in the two halves thereof substantially as indicated. The permanent magnet 40B may be provided with suitable adjusting facilities, such as a screw driver slot, formed in one or both ends. 75 The rotation of the permanent magnet 40B between the

core sections 36B, 37B enables the strength of the permanent magnetic field produced to be adjusted in both magnitude and polarity. Windings 41B, 42B are mounted on the legs of the core pieces 36B, 37B, although alternatively the windings may be wound as a unitary structure and mounted on the main body portion of the core. A set of pole pieces 43B, 44B is provided internally of the neck of the kinescope envelope 35 for each of the convergence magnet assemblies. The internal pole pieces 43B, 44B are arranged to increase the effectiveness of the associated magnet assemblies by decreasing the reluctance of the magnetic circuit and considerably improving the flux distribution of the field produced between the pole pieces. The convergence magnet assemblies 31R—31B produce fields which in the vicinity of the electron beams associated therewith are substantially transverse to the axis of the kinescope. The electron beam associated with each of the magnet assemblies may be readily moved toward or away from the longitudinal tube axis by adjusting the amount of magnetic flux in the respective assemblies 31. The direction and magnitude of such movement is controlled by the energization of the windings 41, 42 and rotation of the permanent magnet 40.

The convergence magnet assemblies 31 may be energized by means of the circuit arrangement shown in Fig. 3. The convergence magnet assemblies may be substantially identical, and may be energized by substantially identical circuits. Therefore, the description will be limited to the particular circuits by which the windings 41 and 42 of the convergence magnet assembly 31 are energized, it being understood that the same description applies equally as well to the circuits illustrated for energizing the other convergence magnet windings except where specifically noted.

Referring to Fig. 3, a synchronizing sawtooth voltage wave of vertical deflection frequency at input terminals 51, 52 is applied by way of connections including a coupling capacitor 58 to a vertical deflection wave amplifying tube 59. Vertical sawtooth current waves are induced in a vertical deflection wave output transformer 60 by a primary winding 61 connected in the anode circuit of the vertical amplifier tube 59. The sawtooth deflection wave appearing across a secondary winding 62 is applied by means including blocking capacitors 63—65 to a vertical deflection system winding comprising sections 66, 67. No provisions are shown in the circuit for deflection centering of the scanning beams, but conventional centering current circuitry may be employed in known manner. A sawtooth voltage wave, at horizontal deflection rate is applied at input terminals 71, 72 of the horizontal amplifying tube 74. A sawtooth current wave is induced by the connections to the amplifying tube 74 in a winding 76 of the horizontal deflection wave output transformer 78. The deflection pulse voltage and sawtooth current wave appearing in the output portion of the winding 76 is applied to a horizontal deflection system winding comprising two sections 81, 82 the latter of which is shunted by an anti-ringing capacitor 83. Again no centering provisions have been shown, but these may be readily supplied according to the known art.

In the example shown in Fig. 3, two different configurations of circuitry according to the invention are shown. One example is shown in connection with the vertical deflection system and the other in connection with the horizontal deflection system, but it should be understood that either may be used in both systems or interchanged, if desired. Furthermore, the converging windings 41 are shown as connected only in the vertical system and the windings 42 as connected only in the horizontal system. It should be understood that those windings 41, 42 may be connected in series or parallel and the separate convergence currents applied to both windings. In such case it is necessary to isolate one source from the other but this is within the skill of those

familiar with the art. An example of such isolating connection is given in the copending U. S. Patent application, Serial No. 539,883 filed October 3, 1955 for "Multi-Beam Convergence Circuits" by Morris D. Nelson.

A parabolic current wave is produced in the vertical beam converging windings 41 by integration of sawtooth vertical deflection waves applied thereto. The sawtooth waves are developed across a plurality of variably tapped resistance elements or potentiometers 91, connected in parallel and interposed in series with the vertical beam deflecting winding sections 66, 67. There is one element for each circuit desired. In the example shown, there is a potentiometer 91R for the red controlling electron beam, another potentiometer 91G for the green controlling electron beam, and a further potentiometer 91B for the blue controlling electron beam. Movement of the arms 92 of the potentiometers 91 serves to adjust the amplitudes of the sawtooth voltage components available for the parabolic current waves for developing the sawtooth current waves. Hence the amplitude of converging the individual electron beams in the vertical direction is likewise varied.

By means of other variably tapped resistance elements or potentiometers 94R, 94G and 94B connected in parallel across a center tapped secondary winding 93 of the vertical deflection wave output transformer 60, positive or negative pulse waveforms at the vertical deflection rate may be obtained by movements of the taps or arms 95 respectively of the resistance elements or potentiometers 94. At an intermediate position of each potentiometer arm, the potential from the arm to the neutral point of reference potential, at the center tap is zero. Alternatively the potentiometers 94 may be center tapped and interconnected to establish a point of reference potential, but this entails more expense than the center tapped winding 93. Moving the potentiometer arm to either side of neutral causes either a positive or negative pulse wave to appear between the arm and the point of reference potential of amplitude proportional to the degree of movement of the arm. The plurality of convergence pole-piece exciting windings 41 are individually connected between the arms 92 of the parabola amplitude controlling potentiometers 91 and the arms 95 of the tilt controlling potentiometers 94.

A color purity magnet is used with tri-color kinescopes of the type mentioned hereinbefore. This magnet operates by directing the three electron beams across the longitudinal axis of the kinescope. This beam movement, together with tube geometry and some component tolerances, makes tilting necessary. The parabolic waves are tilted, or shifted so that the minimum amplitude points are either toward the beginning or the end of the waves, by positioning the arms 95 on the sawtooth wave amplitude setting potentiometers 94. For this reason these potentiometers 94 are usually termed "tilt controls."

In the example shown in Fig. 3, parabolic current wave-forms are also utilized for horizontal convergence of the three beams of the tri-color kinescope 35. A voltage pulse wave of horizontal recurrence rate is obtained from an isolated winding 102 on the horizontal output deflection wave transformer 78. One terminal of this horizontal winding is maintained at a point of reference potential, shown as ground, to which the converging windings 42 are returned. The other terminal of the converging winding 102 is connected to series circuits comprising an adjustable inductance element 104, a compensating capacitive element 105 and a resistance element 106 having an impedance low with respect to that of the inductance element 104. The converging windings 42 are connected in shunt to those portions of the series circuit comprising the compensating capacitor 105 and the resistance element 106. The series circuit is predominately inductive, thereby producing an approximately sawtooth voltage across the resistance element 106. The compen-

sative capacitance element 105 deforms the sawtooth wave to render it slightly S-shaped and symmetrical to provide a more perfect parabolic current waveform in the converging windings 42. In addition larger values of resistance elements 106 may be used, resulting in lower power loss and less loading on the high voltage rectifier.

With the adjustable inductor 107B removed from the circuit, adjustment of the blue controlling electron beam integrating inductance element 104B varies the amplitude of the sawtooth current waveform flowing in the blue converging winding 42B. The phase of the parabolic sawtooth wave is controlled, or "tilted," by varying the value of resistance of the resistance element 106B, which alters the RC constant of the series circuit portion comprising the capacitance element 105B and the resistance element 106B. Variation of this resistance element 106B changes the integration, resulting in a change in phase of the parabolic current waveform in the converging winding 42B. Such an arrangement as described may be used for all three of the converging windings 42R-42B.

One type of tri-color kinescope has the three color controlling electron beam generating guns so oriented within the envelope of the kinescope 35 and so energized in accordance with the present Federal Communications Commission Standards for color television broadcasting wherein the blue color controlling electron beam is subject to an effect known as "drooping." The other two electron beam forming guns are arranged substantially side by side with the kinescope 35 in position for operation, and energized in accordance with the regulations whereby "drooping" is not a problem and whereby closely similar operating characteristics are obtained from the other two electron guns. The "drooping" and similar characteristics are eliminated according to the invention by shunting the resistance element 106B by an inductance element 107B. The inductance element 107B may be adjustable to phase or "tilt" the parabolic current waveform so that the resistance element 106B need not be adjustable, but an adjustable resistance element 106B and a fixed inductor may be used, or both may be adjustable as desired. The addition of the inductance brought about by the inclusion of the inductor 107B improves the integrating action in such manner as to eliminate the "drooping" characteristic. This arrangement may be used for all three of the converging windings 42 if the integrating action is insufficient for use with the particular type of tri-color kinescope tube under consideration.

As shown in Fig. 3 the adjustment of the convergence circuits for the red and green color controlling electron beams is rendered easier and quicker by dividing the inductance element 104 and the resistance element 106 into three portions so that adjustment of the total inductance and the total resistance in each of the convergence circuits controls the amplitude and tilt of the parabolic current waveforms for the two circuits simultaneously. Portions of the inductance element 104 and the resistance element 106 are arranged for differential adjustment so that the two electron beams are made to operate in the same desired manner without requiring further adjustment of the total inductance and total resistance in the two convergence circuits. The adjustable inductor 104RG is connected in series with two differential inductors 104R and 104G. Any means of varying the inductance in these inductors may be used. Molded adjustable ferrite cores are suggested as a readily available and simple means. The differential inductors 104R and 104G are wound on a suitable form and tuned by a single ferrite core which may be adjusted to vary the inductance of one inductor 104R, for example, with respect to the other inductor 104G without disturbing the total inductance presented to the common circuit connected adjustable inductor 104RG. In similar manner the resistance element 106R-G of a tilt "balancing" potentiometer is coupled to both the red and green convergence circuits

by means of compensating capacitors 105R and 105G. The arm of the balancing potentiometer 106R-G is connected to one terminal of a variable resistance element 106RG, the other terminal of which is connected to the point of fixed reference potential, shown as ground. Thus, varying the adjustable resistance element 106RG will vary the total resistance in the two convergence circuits and determine the tilt, while adjustment of the differential resistance element 106R-G serves only to apportion the resistance between the two convergence circuits.

With tri-colored kinescopes of the type described, the electron guns are mechanically tilted toward the central axis of the kinescope so that the individual beams virtually converge at the center of the phosphor screen. However, because of manufacturing tolerances, a static component of magnetic field is necessary to set the beam direction of each gun precisely. This field is obtained by means of the rotatable permanent magnets 40 in the convergence coil assemblies 31 as shown in Fig. 2. The field required is a function of the error and the square root of the 10 ulti potential, the latter of which follows the power line voltage in shunt tube high voltage regulating systems. Both the vertical and the horizontal dynamic convergence waves are applied to the converging windings 41, 42 for alternating current flow only. When the 15 components of magnetic field these voltages produce are added to the static component required for center convergence as previously adjusted, the total field when scanning the center of the raster will be in error by an amount equal to the instantaneous value of the dynamic 20 convergence voltage. This error may be corrected by adding a compensating field of equal value and opposite sign by means of resistance elements 108 which are 25 connected to a source of intermediate potential obtained from the same low voltage rectifier that supplies the 30 circuits developing the dynamic components; that is, the horizontal and vertical deflection wave translating stages whose outputs vary directly with the power line voltage. In the circuit as shown in Fig. 3 the compensating field 35 varies in the same manner as the dynamic fields so that for normal power line voltage variations, there is high 40 degree of tracking over the raster, resulting in excellent 45 beam convergence. The centering currents may be applied only to the vertical converging windings as shown, only to the horizontal converging windings, or they may be applied to both, as in the case of interconnected converging windings.

Those skilled in the art will determine the values of 50 components to be used in various applications of the invention from the teachings herein, however, the values of pertinent components listed below which were used in a successfully operated color television receiver having 55 convergence systems as shown in Fig. 3, are given as a guide in the practice of the invention.

Ref. No.	Component	Type or Value
35	Tri-color kinescope	21A XP22.
41, 42	Convergence system winding	1,200 turns on 0.5 mh. winding on $\frac{5}{8}$ " ferrite cores.
50	Vertical amplifier tube	6BL7 (parallel).
74	Horizontal amplifier tube	6CD6.
88	Cathode resistor	270 ohms.
87	Vertical linearity control	0-1 kilohm.
91	Vertical parabola control	0-100 ohms.
93	Vertical tilt winding	± 10 v.-to-ground.
94	Vertical tilt control	0-100 ohms.
98	Series resistor (Blue only)	75 ohms.
106	Horizontal pulse wave source	100 v.-to-ground.
104	Horizontal integrating inductors	0.2-1.2 mh. (differential inductors 104R and 104G with slug in center 0.9 mh.)
105	Compensating capacitors	0.5 mfd.
106	Series resistors	0-30 ohms.
106B	Series resistor	40 ohms.
106RG	Common resistor	0-40 ohms.
106R-G	Differential resistor	20 ohms.
108	Dropping resistors	82 kilohms.

The power supply delivered approximately 400 volts between the points marked + and ground.

The invention claimed is:

1. A beam convergence circuit arrangement for a multibeam kinescope, the electron beams of which are deflected in two directions normal with respect to each other, including a plurality of electron beam converging windings through which currents of substantially parabolic waveform of frequency corresponding to electron beam deflection in one of said directions are desired, a plurality of series circuits each comprising an inductance element, a capacitance element, and a resistance element connected in series, means to apply a voltage pulse train of recurrence rate corresponding to said deflection in said one direction across said series circuits, means to couple said beam converging windings individually across at least said resistance elements of said series circuits, and an inductance element shunted across at least one of said resistance elements, a plurality of other electron beam converging windings through which currents of substantially parabolic waveform of frequency corresponding to electron beam deflection in the other of said directions are desired, a plurality of adjustably tapped resistance elements connected in parallel and having the adjustable taps individually connected to given terminals of said other electron beam converging windings, another electron beam deflecting winding connected in common to given terminals of said resistance elements, means to apply deflection waves of frequency corresponding to electron beam deflection in said other direction between the other terminals of said resistance elements and the other terminal of said other beam deflecting winding, a number of adjustably tapped resistance elements connected in parallel and having adjustable taps individually connected to the other terminals of said other beam converging windings, a winding connected to the terminals of the last said parallel connected resistance elements for applying a voltage pulse thereto of recurrence rate corresponding to electron beam deflection in said other direction, and a connection between an intermediate point of said interconnected windings and parallel connected resistance elements and the other terminals of the first said parallel connected resistance elements.

2. A beam convergence circuit arrangement for a multibeam kinescope, the electron beams of which are deflected in two directions normal with respect to each other, including a plurality of electron beam converging windings through which currents of substantially parabolic waveform of frequency corresponding to electron beam deflection in one of said directions are desired, a plurality of series circuits each comprising an inductance element, a capacitance element, and a resistance element connected in series, means to apply a voltage pulse train of recurrence rate corresponding to said deflection in said one direction across said series circuits, means to couple said beam converging windings individually across at least said resistance elements, and an inductance element shunted across at least one of said resistance elements, at least one of said shunt connected elements being adjustable.

3. A beam convergence circuit arrangement for a multibeam kinescope, the electron beams of which are deflected in two directions normal with respect to each other, including a plurality of electron beam converging windings through which currents of substantially parabolic waveform of frequency corresponding to electron beam deflection in one of said directions are desired, a plurality of adjustably tapped resistance elements connected in parallel and having the adjustable taps individually connected to given terminals of said electron beam converging windings, an electron beam deflecting winding connected in common to given terminals of said resistance

elements, means to apply deflection waves of frequency corresponding to electron beam deflection in said one direction between the other terminals of said resistance elements and the other terminal of said beam deflecting winding, a number of adjustably tapped resistance elements connected in parallel and having adjustable taps individually connected to the other terminals of said beam converging windings, a winding connected to the terminals of the last said parallel connected resistance elements for applying a voltage pulse thereto of recurrence rate corresponding to electron beam deflection in said one direction, and a connection between an intermediate point of said interconnected windings and parallel connected resistance elements and the other terminals of the first said parallel connected resistance elements.

4. A beam convergence circuit arrangement for a multibeam kinescope, the electron beams of which are deflected in two directions normal with respect to each other, including a plurality of electron beam converging windings through which currents of substantially parabolic waveform of frequency corresponding to electron beam deflection in one of said directions are desired, a plurality of series circuits each comprising an inductance element and a resistance element common to all of said series circuits, a plurality of series circuits each comprising a differential inductance element, a capacitance element and a differential resistance element, means coupling said series circuits in parallel between given terminals of said common inductance element and said common resistance element, means to apply a voltage pulse train of recurrence rate corresponding to said deflection in said one direction between the other terminals of said common inductance element and said common resistance element, means to couple said electron beam converging windings individually between the other terminal of said common resistance element and the junctions between said differential inductance elements and said capacitance elements.

5. A beam convergence circuit arrangement for an internal convergence pole-piece type multi-beam kinescope electron beams of which are deflected in two directions normal with respect to each other by common electron beam deflecting fields, including a plurality of electron beam converging windings through which currents of substantially parabolic waveform of frequency corresponding to electron beam deflection in one of said directions are desired, an inductance element having two differential terminals and a common terminal arranged to present the same total inductance between each of the differential terminals and the common terminal with inductance varying differentially between the two differential terminals, an adjustable resistance element having differential terminals and a common terminal and arranged to present the same total resistance between said differential terminals while varying the resistance between said differential terminals and said common terminal, capacitance elements interconnecting individually the differential terminals of said inductance element and said resistance element, means to apply a voltage pulse train of recurrence rate corresponding to said deflection in said one direction between said common terminals of said inductance and said resistance elements, and means to connect said electron beam converging windings individually between the junctions of said capacitance and inductance elements and said common terminal of said resistance element.
